UNITED STATES PATENT OFFICE.

EDWARD HAROLD PARKER, OF BELLEVILLE, NEW JERSEY, ASSIGNOR OF ONE-HALF
TO CLARENCE H. MATHEWS, OF CLEVELAND, OHIO.

WIRE ROPE.

Application filed August 12, 1921. Serial No. 491,719.

To all whom it may concern:

Be it known that I, EDWARD HAROLD PARKER, a citizen of the United States, and a resident of Belleville, in the county of Essex and State of New Jersey, have invented certain new and useful Improvements in Wire Ropes, of which the following is a specification.

This invention relates to wire ropes and is particularly although not exclusively designed to be used in connection with elevators of the type known as traction elevators. In elevators of this type, the cable passes over a motor driven sheave provided with U-shape or V-shape grooves; and the rope is propelled by friction between the walls of the grooves and the rope. It will be understood that the greater the wearing surface, that is actual rotundity, of the rope the better; and this is especially true when using the cable in connection with a sheave having V-shape grooves. In order to obtain the requisite rotundity, it is customary to make the rope as large as possible and to obtain the requisite cushioning, to provide it with a core of hemp or other material of relatively large size. In practice, it has been found that, under the severe conditions of strain and stress to which cables of this character are subjected, the core will frequently collapse thereby destroying the rotundity, and by that the usefulness, of the rope because of the material decrease in wearing surface occasioned thereby. The main object and feature of this invention is to obviate these difficulties.

In the accompanying drawings the invention is disclosed in a concrete and preferred form in which—

Fig. 1 is a view in elevation of a length of rope embodying the invention.

Fig. 2 is a transverse sectional view on the line 2—2 of Fig. 1.

Fig. 3 is a fragmentary sectional view showing one method of forming the intermediate core.

Fig. 4 is a fragmentary sectional view showing another method of forming the intermediate core.

1 indicates a core of any suitable material such as hemp, or the like, around which are laid six inner strands 2, each strand

being composed of a plurality of wires 3 (here seven in number) twisted together. 4 indicates a plurality of outer strands, in number twice that of the inner strands, each outer strand being composed of a number of wires 5 twisted together. The diameter of the outer and inner strands and the number and diameter of the wires of both the inner and outer strands are alike. The outer strands can therefore be laid around the inner strands in the manner indicated in Fig. 2 where it will be observed that one alternate set of outer strands, indicated by 4^a, will come directly over the inner strands and will be radial to and in contact with the inner strands. The thrust on the set 4^a of outer strands will therefore be transmitted directly to core 1. Interposed between the other alternate set of outer strands, indicated by 4^b, and the inner strands is an auxiliary core 6 which receives the thrust of said other alternate set of outer strands 4^b. I have found that by the foregoing means a large rope having requisite wearing surface is produced; that the rope is flexible and pliable; and that the center core does not tend to collapse or flatten. The auxiliary core may be produced in different ways. In some instances a simple strand of fibrous material indicated by dotted circle 7 in Fig. 3 is laid between the inner strands and a member of set 4^b of the outer strands while, in other instances, I prefer to use two strands of fibrous material, indicated by dotted circles 8 in Fig. 4. That is to say: either six or twelve strands of fibrous material. In either event, the fibrous material is, during the laying of the rope, 90 squeezed into the interstices between the inner and outer metallic strands.

I claim:

A wire rope comprising: a fibrous core, a plurality of inner strands laid around said core, each strand being composed of a plurality of wires twisted together, a plurality of outer strands, in number twice that of the inner strands, and each outer strand being composed of a plurality of wires twisted together, the diameter of the inner and outer strands and the number and diameter of the wires of both the inner and outer strands being the same and said outer strands being

laid around the inner strands with one set of alternate outer strands radial to and in contact with the inner strands, to thereby transmit the thrust of said set of alternate outer strands to the core, and a circumferentially discontinuous intermediate core between the inner and outer strands to receive

the thrust of the other alternate set of outer strands.

Signed at New York city, in the borough ¹⁰ of Manhattan, county and State of New York, this 11th day of August, 1921.

EDWARD HAROLD PARKER.
